[57] **CLAIM**

The ornamental design for a skid-steer loader pivot wheel arm design, as shown and described.

DESCRIPTION

FIG. 1 is a left side and front perspective view of the skid-steer loader pivot wheel arm design showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing of the skid-steer loader in FIG. 1 is for illustrative purposes only, and forms no part of the claimed design.
